D12-9.

OR D 12,417 EX

12417

UNITED STATES PATENT OFFICE.

FRANK B. MILLER, OF ENON, OHIO.

DESIGN FOR A SLEIGH.

SPECIFICATION forming part of Design No. 12,417, dated August 16, 1881.

Application filed July 20, 1881. Term of patent 14 years.

To all whom it may concern:

Be it known that I, FRANK B. MILLER, of Enon, in the county of Clarke and State of Ohio, have invented a new and Improved Design for 5 Sleighs, of which the following is a full, clear, and exact description.

The accompanying photograph is a side view of my newly-designed sleigh.

The design relates to the shape or configuration of the sides forming the body of the sleigh.

10 A A in the photograph are the sides, shaped in the form of deer, and carved on their outer surfaces to give life-like form to the head, flanks, and other parts. The legs a are secured on curved runners b, that terminate at the forward ends with crossed arrows d. At 15 the rear and between the deer sides A is the

seat, the sides c of which curve upward and backward and give a graceful finish to the rear 20 part of the sleigh-body.

This design gives a light and graceful appearance to the sleigh, besides being entirely appropriate.

Having thus described my invention, I claim 25 as new and desire to secure by Letters Patent—

1. The design for sleighs herein shown and described, which consists of the deer-shaped sides A and the seat having curved sides c.

2. The design for sleighs herein shown and 30 described, which consists of the deer-shaped sides A and the curved runners b.

FRANK BISHOP MILLER.
